ATTORNEY

WITNESS:

UNITED STATES PATENT OFFICE.

THEODORE H. GRAF, OF LOUISVILLE, KENTUCKY, ASSIGNOR TO SOUTHERN SIGNAL COMPANY, INC., OF BIRMINGHAM, ALABAMA.

GRATE AND MOUNTING.

Application filed April 29, 1922. Serial No. 557,360.

To all whom it may concern:

Be it known that I, THEODORE H. GRAF, a citizen of the United States, residing at Louisville, in the county of Jefferson and State of Kentucky, have invented new and useful Improvements in Grates and Mountings, of which the following is a specification.

This invention relates to grate mountings for use in fire places and has for its object the provision of a grate mounting whereby a basket or other similar type of grate may be supported within the fire place frame regardless of the distance between the supporting lugs provided on the frame for supporting the grate.

It is well known that no two manufacturers of grates make the supporting lugs for the grate the same distance apart and as the grates seldom, if ever, bear the names of the manufacturers it becomes a difficult matter for the retail dealers to supply the proper grate to a customer desiring to make a replacement and this of course results in necessitating trying the different grates to see if they fit within the frames, this resulting in a great degree of annoyance and inconvenience and involving a waste of time.

It is with these facts in view that I have designed the present device which provides means on a grate for engaging it within any grate frame of a standard size.

An additional object is the provision of a device of this character which will be simple and inexpensive in manufacture, highly efficient in use, a great time and labor saver and a general improvement in the art.

With the above and other objects and advantages in view the invention consists in the details of construction to be hereinafter more fully described and claimed, and illustrated in the accompanying drawings, in which:

Figure 1 is a front view of a grate engaged within a frame and showing the grate as equipped with the device, parts of the frame being broken away to show the structure,

Figure 2 is a fragmentary perspective view of a portion of a grate frame,

Figure 3 is a detail perspective view of one corner of the grate.

Referring more particularly to the drawings the letter A designates an ordinary grate frame which, as is well known, is provided at the confronting sides of the opening therein with pairs of vertically spaced grate supporting lugs B and C. In carrying out the present invention I provide the grate D at each end with a hook 10, these hooks being designed to engage over the uppermost supporting lugs B. Formed on each end of the grate below the hook 10 is an elongated angle bracket 11 which acts as a guide and brace when engaged upon the lower lug C.

In installing the grate it is inserted in the usual manner with the hooks 10 engaging the upper lugs B and the brackets 11 engaging the lower lugs C. In this way it will be seen that it makes no difference how close together or how far apart the lugs B and C may be as the elongation of the brackets 11 amply takes care of all such variations.

From the foregoing description and a study of the drawings it will be apparent that I have thus provided a very simple grate mounting which will be highly effective and advantageous in making all grates interchangeably mountable within different makes of grate frames thus obviating the necessity of purchasing new grates from the original manufacturer of the burnt out grate.

While I have shown and described the preferred embodiment of the invention, it is of course to be understood that I reserve the right to make such changes in the form, construction and arrangement of parts as will not depart from the spirit of the invention or the scope of the subjoined claims.

Having thus described my invention I claim:

1. In combination, a fire place grate frame provided at its confronting edges with upper and lower lugs extending toward each other and formed integrally upon the frame, and a grate formed at the rear side of its upper corners with integral hooks engageable over the upper ones of said lugs, the

grate being further formed on its rear side with brackets integral thereon and engageable over the lower lugs, said brackets being L-shaped in cross section with their free ends directed outwardly.

2. Means for mounting a grate within a fire place grate frame provided at its confronting edges with spaced lugs, comprising hooks formed at the upper corners of the

grate and engageable over the upper lugs, 10 and vertically elongated brackets on the ends of the grate engageable with the lower lugs, said hooks and brackets being formed integrally upon the grate itself and said bracket being of L-shape in cross section. 15

In testimony whereof I affix my signature.

THEODORE H. GRAF.
